(57) **CLAIM**

The ornamental design for a golf divot repair tool, as shown and described.

DESCRIPTION

FIG. 1 is a front perspective view of golf divot repair tool in accordance with the present invention;

FIG. 2 is a front side elevational view of the present disclosure;

FIG. 3 is a right side elevational view thereof;

FIG. 4 is a rear side elevational view thereof;

FIG. 5 is a left side elevational view thereof;

FIG. 6 is a top side elevational view thereof; and,

FIG. 7 is a bottom side elevational view thereof.

It will be understood that the broken lines shown in the figures illustrate environmental structure associated with the present invention but forms no part of the claimed design.

1 Claim, 4 Drawing Sheets
